DESIGN FOR A POT LIFTER

Ralph Homer Moyer, Detroit, Mich.

Application February 2, 1939, Serial No. 82,728

Term of patent 7 years

To all whom it may concern:

Be it known that I, Ralph Homer Moyer, a citizen of the United States and a resident of Detroit, county of Wayne, and State of Michigan, have invented a new, original, and ornamental Design for a Pot Lifter, of which the following is a specification, reference being had to the accompanying drawing, forming part thereof.

Fig. 1 is a perspective view of the pot lifter, showing my design;

Fig. 2 is a top plan view; and

Fig. 3 is a side elevational view thereof.

I claim:

The ornamental design for a pot lifter, as shown.

RALPH HOMER MOYER.
